CLAIM

The ornamental design of a coffee bean roaster display unit, as shown and described.

DESCRIPTION

FIG. 1 is a front perspective view of a coffee bean roaster display unit showing my new design in full lines with broken lines showing the associated environmental matter for illustrative purposes only and forming no part of the claimed design;

FIG. 2 is a front elevational view of the coffee bean roaster display unit in full lines and the environmental matter showing in broken lines;

FIG. 3 is a right side elevational view of the coffee bean roaster display unit in full lines and the environmental matter showing in broken lines;

FIG. 4 is a left side elevational view of the coffee bean roaster display unit in full lines and the environmental matter showing in broken lines;

FIG. 5 is a top plan view of the coffee bean roaster display unit in full lines and the environmental matter showing in broken lines;

FIG. 6 is a bottom plan view of the coffee bean roaster display unit in full lines and the environmental matter showing in broken lines;

FIG. 7 is a rear elevational view of the coffee bean roaster display unit in full lines and the environmental matter showing in broken lines; and,

FIG. 8 is a rear elevational view of the coffee bean roaster display unit without the broken lines of the associated environmental matter.
